HOLDER FOR MATCH FOLDERS

William N. Bachman, Glendale, Mo.

Application March 30, 1949, Serial No. 1,719

Term of patent 7 years

(CL. D80—9)

To all whom it may concern:

Be it known that I, William N. Bachman, a citizen of the United States, residing in the city of Glendale and State of Missouri, have invented a new, original, and ornamental Design for a Holder for Match Folders, of which the following is a specification, reference being had to the accompanying drawing, forming part thereof.

In the drawing,

Fig. 1 is a cross sectional view taken on line 1—1 of Fig. 2.

Fig. 2 is a top plan view of a holder for match folders showing my new design; and

Fig. 3 is an end view thereof.

I claim:

The ornamental design for a holder for match folders, substantially as shown.

WILLIAM N. BACHMAN.
